A. R. BEHNKE

ELECTRICALLY OPERATED FUEL INJECTOR

Filed April 9, 1919

Inventor:

Albert R. Behnke,
by: ~~Amelia~~ Attorney.

UNITED STATES PATENT OFFICE.

ALBERT R. BEHNKE, OF ST. PAUL, MINNESOTA.

ELECTRICALLY-OPERATED FUEL INJECTOR.

Application filed April 9, 1919. Serial No. 288,871.

To all whom it may concern:

Be it known that I, ALBERT R. BEHNKE, a citizen of the United States, residing at St. Paul, in the county of Ramsey and State of Minnesota, have invented a new and useful Improvement in Electrically-Operated Fuel Injectors, of which the following is a specification.

This invention relates to electrically operated injectors for injecting hydrocarbon into internal combustion engines and its object is to provide such an injector operated by electro-motive force from any suitable source of electrical energy, injecting the hydrocarbon directly into the explosion chamber of the internal combustion engine with means for automatically relieving the excess pressure of the injector, the automatic means being adjustable to different pressures. An injector of this kind is a great advantage, for the reason that the hydrocarbon or liquid fuel is introduced directly into the explosion chamber before any of it has had an opportunity to vaporize or condense before entering the explosion chamber, thereby giving a device which is economical and efficient.

The electrical operation of the injector eliminates ordinary mechanical means which would be necessary to operate the same making it possible to place the injector in any convenient position and giving a most simple device. The injector is provided with means for adjusting the pumping capacity of the same and means for making the device practically noiseless in operation. It is obvious that the injector can be used on any style or construction of internal combustion engines by properly wiring the same to a suitable source of electrical energy with the proper construction of timing switch or commutator so as to cause the injector to pulsate at the desired time.

In the drawings, Figure 1 illustrates the injector in enlarged form partly in cross section and diagrammatically illustrating the injector connected to an internal combustion engine, together with the electrical connections therefor.

Figure 2 is a detail of the nozzle of the engine part of which is broken away and illustrated in cross section.

Figure 3 is a side elevation partly illustrated in cross section of an alternative form of injector, the electric wiring of which is illustrated diagrammatically.

Figure 4 is an end elevation of the construction illustrated in Figure 3.

In the drawing, the injector A is illustrated in enlarged form and an internal combustion engine B only a portion of which is illustrated, is very much smaller than it would be in proportion to the injector in actual construction. The present representation being made to conveniently describe and explain the construction and functions of the injector.

The injector A is formed with two electro-magnetic coils 1 and 2 which are of ordinary construction with a proper number of windings and wire so as to operate with any desired electrical current or source of energy.

Centrally disposed between the coils is a plunger rod 3, which is slidably held with an armature portion 4 rigidly secured near its outer end 5. The outer end 5 of the plunger rod 3 is slidably held in the bearing portion 6 and a coil spring 7 is adapted to bear against the end of the rod 3 so as to cushion the same and limit the movement of the rod in one direction. The spring 7 is held in the hollow adjusting nut 8 which is threaded on the outer extremity of the bearing portion 6 of the injector. By turning the nut 8, the pressure of the spring 7 against the rod 3 is adjusted.

The bearing portion 6 is formed of brass or non-metallic material and is connected by means of the screws 9 to the soft iron portions 10 which are secured to the outer ends of the magnets 1 and 2 by means of the screws 11. The portions 10 are adapted to extend in close proximity to the armature 4 of the magnetic coil A so that the armature will be easily influenced by electro-magnets 1 and 2.

The coil spring 12 is positioned about the rod 3 between the magnets 1 and 2 and is adapted to bear against one side of the armature 4 and against the inner bearing portion 13 of the magnet A to tend to force the armature 4 away from the magnets 1 and 2 and pressing the end 5 of the rod 3 against the spring.

The portion 13 is of soft iron and connects across the magnets 1 and 2. A brass or non-magnetic metallic bushing extends centrally through the portion 13 and forms a bearing for the plunger rod 3 of the injector.

The injector is formed with a vacuum body portion 15 which is held by means of the bracket or support 16 to the inner end

- of the magnetic coils 1 and 2. The bracket 16 is secured to the portion 13 by means of screws 17. The bracket portion 16 together with the body portion 15 are preferably formed with brass or other non-magnetic material, thereby preventing any interference with the magnetic lines of force passing through the magnet coils or connecting parts.
- 5 The body portion 15 is securely held to the bracket portion 16 by means of the nut 19 which is threaded on the inwardly projecting end of the body portion 15.
- 10 The plunger rod 3 is adapted to extend into the vacuum chamber 20 of the body portion 15 so that when the rod 3 is reciprocated back and forth, a vacuum will be caused in the chamber 20.
- 15 Suitable packing 21 is held about the inner end of the rod 3 by means of the packing nut 22 in the ordinary manner. The chamber portion 20 is connected by means of a vertical passageway 23 with the passages of the check valves 24 and 25. The check valves 24 and 25 being of the ordinary ball type construction. The lower check valve 24 is connected to a supply pipe 26 and it is understood that the supply pipe would connect with a tank or any suitable container 25 for a supply of hydrocarbon. (The supply tank not being illustrated.)
- 20 The upper check valve 25 is connected by a pipe 27 to a by-pass or relief valve 28. The valve 28 is constructed with two outlets 30 or passage-ways, one of which is connected by the pipe 29 with the spray nozzle 30. The spray nozzle 30 is positioned in the head of the engine cylinder B so as to spray the liquid fuel directly into the combustion 35 chamber. The other passage-way of the valve 28 is connected by a pipe 31 to the supply tank, to which the pipe 26 is connected. A ball check 32 is positioned in the chamber 33 of the valve 28 and is held in 40 closed position by means of the coil spring 34. The pressure of the spring 34 is variable by means of the adjusting rod 35 which is threaded in the valve casing and the inner 45 end of which bears against the disk 36. The disk 36 bears against the spring 34 to compress the same when the rod 35 is screwed inward and to relieve the compression of the spring when the rod 35 is screwed outwardly. Thus the adjustable relief or by-pass valve 28 is so constructed as to regulate 50 the injecting pressure in the pipes 27 and 29 and also through the nozzle 30, during the operation of the injector A.
- 55 The nozzle 30 is formed with a check valve as is illustrated in Figure 2 which consists of a coil spring 37 positioned in the lower extremity of the nozzle and which is adapted to bear against the ball check 38 to close the passage-way 39 of the injector 60 when compression takes place in the combustion chamber C of the engine cylinder B and during the firing of the internal combustion engine, but allowing the ball check to open when the injector operates so as to inject the desired amount of fuel into the combustion chamber C of the engine B. The nozzle 30 is formed with a small opening 40 on its lower or injecting end through which the fuel passes when the injector A is operated. It being obvious that the hole 40 can be of various sizes to suit the requirements of the engine on which the injector is used but it is preferably small and thereby prevents a strong-back pressure into the nozzle when the engine fires. The ball check 38 prevents any back firing from the explosion chamber C into the nozzle 30 and pipe 29, due to the fact that the pressure would raise the ball check 38 against the lower end of the passage-way 39 closing the same even if the spring 39 was inoperative or not present.
- 65 The electro-magnetic coils 1 and 2 of the injector A are connected in series by the wire 41 and the coil 2 is grounded at G 70 while the coil 1 is connected by means of the wire 42 to an electric battery 43 or any other suitable source of energy and by means of the wire 44 to the brush 45. The brush 45 is adapted to bear against the commutator segment 46 and an insulated portion 47 which are positioned on the crank shaft 48 of the engine B or on any other suitable shaft so as to properly time the 75 operation of the injector A. The shaft 48 is grounded by means of the wire 49.
- 80 In operation, as the engine reciprocates and the crank shaft 48 rotates, the brush 45 will contact with the segment 46 closing the electric circuit through the wire 44, battery 43, wire 42, coil 1, wire 41, coil 2, through the ground and through the wire 49 to the crank shaft 48, sending an electric-current into the coils 1 and 2, and thereby drawing the armature 4 inward against the spring 12 85 into the position illustrated in Figure 1, forcing the plunger rod 3 of the injector into the vacuum chamber 20, raising the check valve 25 and forcing liquid fuel from the chamber 20 through the pipe 27 through 90 the valve 28, pipe 29 and out of the spray nozzle 30 into the combustion chamber C of the engine. When the crank shaft 48 rotates so that the brush 45 contacts with the insulated segment 47, the electric-current 95 from the battery 43 is cut off from the coils 1 and 2 and the spring 12 will force the plunger rod 3 out against the spring 7 away from the portions 10 of the coils 1 and 2. The spring 7 cushions the rod so as to prevent any sharp jar and eliminating noise of the plunger rod and the plunger rod 3 will 100 form a suction in the chamber 20. The check valve 25 closes automatically by gravity and the valve 24 opens due to the suction 105

of the plunger rod 3, drawing into the chamber 20 a charge of liquid fuel from the supply tank to which the pipe 26 is connected. When the brush 45 again contacts with the segment 46, the plunger rod 3 will be forced into the chamber 20 forcing the liquid fuel through the nozzle 30 into the combustion chamber again. This operation can be repeated as rapidly as desired during the operation of the engine B, it being obvious that one or more contacting segments 46 can be positioned about the shaft 48 so as to inject fuel into the combustion chamber C at the proper time during the operation of the engine. The length of the stroke of the plunger 3 can be varied by adjusting the threaded nut 8 so as to compress the spring 7 or allow it to expand. The spring 7 bears against the ends of the rod 3. The relief or by-pass valve 28 allows the excess fuel pumped by the injector A to be returned to the supply tank through the pipe 31 and the check 32 of the valve 28 is adjusted by turning the rod 35 so as to compress the spring 34 so that the valve 32 will not open unless the pressure gets above a certain amount. After the valve 28 has been adjusted to the engine to which the injector A is attached, it is not necessary to re-adjust it, as it will automatically operate so that the injector will inject the desired amount of fuel to give the best results from the engine to which the injector is attached. Thus the valve 28 prevents any change in the pressure at which the fuel is injected no matter whether the injector operates fast or slow, thereby keeping the injecting pressure constant after the valve 28 is set.

The alternative construction illustrated in Figure 3 shows the injector coils 1 and 2 connected to a disk like body portion 50 which is preferably of non-magnetic metal and the armature 51 is connected by the screw 52 to the center or axis of a thin diaphragm 53. The diaphragm 53 is preferably of spring metal and is clamped to the portion 50 which is held about the periphery by a clamping ring 54 and screws 55 to the portion 50. The portion 50 is formed with a hollow chamber E and the spring diaphragm 53 forms a cover for the chamber. The diaphragm 53 is so formed as to curve outward, thereby enlarging the chamber E when the diaphragm 53 is in normal position. The portion 50 is formed with inlet passage-way 56 at the bottom and an outlet passage-way 57 at the top. Both the passage-ways 56 and 57 have ball checks 58 positioned therein to close the passage-ways automatically when it is desired during the operation of the injector diaphragm 53. The inlet passage-way 56 is connected by a pipe 59 to the fuel supply tank similar to that to which the pipe 26 is connected and not being illustrated in the drawing, as the tank is

of ordinary construction. The outlet pipe 60 is similar to the pipe 27 and connects with the automatic relief valve 28, pipe 29, nozzle 30 and by-pass 31 so as to inject fuel into the combustion chamber C of an engine during the operation of the injector. The injector coils 1 and 2 in the construction illustrated in Figure 3, are connected by the electric wires 42 with the battery 43, and the ground G, it being understood that the wire 44, only a part of which is shown, is connected in a similar manner as illustrated in Figure 1 to a brush 45 and timing mechanism such as the crank shaft 48. Thus during the operation of the engine B in the use of the injector illustrated in Figure 3, electric-current would be introduced into the coils 1 and 2 and the armature 51 drawn toward the coils 1 and 2 reducing the size of the chamber E thereby forcing liquid fuel into the combustion chamber C in a similar manner as described in Figure 1. When the circuit is broken and no electro-motive force is passing through the coils 1 and 2, the armature 51 will return to the position illustrated in Figure 3, due to the spring nature of the diaphragm 53, causing a suction on the intake pipe 59 and filling the chamber 62 with liquid fuel from the supply tank.

Thus in the operation of the engine, the injector illustrated in Figure 3, will operate rapidly reciprocating the diaphragm 53 back and forth, causing a pump action and thereby injecting liquid fuel into the combustion chamber of the engine. In Figure 4, a priming plug 61 is illustrated at the top of the portion 50 of the injector so that in starting the injector illustrated, the same can be primed to fill the chamber E with hydrocarbon or liquid fuel if it has become empty, so as to give immediate results from the injector when the engine is operated.

In both constructions of injectors illustrated and described, liquid fuel is injected directly into the combustion chamber of the engine by electro-motive force, preventing any loss of fuel through condensation or evaporation before the fuel has been introduced into the combustion chamber, thus giving the greatest amount of efficiency out of the fuel injected and preventing gasification of any portion of the fuel before it enters the combustion chamber. The injectors are of simple construction, quick and positive in operation, being operated by electrical impulses which are directed through the coils when the circuit is closed by the brush and contacting segment.

The injector can be made very small in proportion to the size of the engine and sufficient pressure can be obtained with the injector to inject the fuel with considerable force into the combustion chamber.

In the use of the injector when the combustion engine is cold, such as in starting,

the injection of the fuel directly into the combustion chamber takes the place of ordinary priming, making the engine start easily, while after the engine warms up and even becomes hot, all the gasification of the fuel takes place inside the combustion chamber. The electrical operation of the injector simplifies the whole construction and gives a device which is more positive and efficient than mechanical or air operated fuel carbureters. The injector can be secured in any convenient place, preferably attached to the engine so as to make a very short injecting pipe.

15 The electrically operated injector can be used on the hit and miss engine and by a governor the injector can be shut off so as not to operate or turned on to govern the speed of the engine.

20 What I claim as new and desire to secure by Letters Patent of the United States is:

1. An injector, comprising, an electro-magnet, an armature adapted to be reciprocated by said magnet, pump means connected to said armature and resilient means for adjusting said pump means to vary the pumping capacity of said injector.

2. An electrically operated pump comprising a pair of electro-magnets, core members connected with said electro-magnets and extending outwardly beyond the ends of the same, said core members being formed with oppositely extending faces, an armature adapted to move between said faces and pump means secured to said armature.

3. An electrically operated fuel injector comprising an electro-magnet, a piston attached to the armature of said magnet, and resilient means for adjusting the stroke of said piston and adapted to cushion the stroke of said piston to overcome the back-slap thereof.

4. An electrically operated pump comprising a horse-shoe electro-magnet having a core, core extensions secured to said core, said extensions having oppositely positioned faces, an armature adapted to move axially between said faces and pumping means connected to said armature.

5. A fuel injector comprising a pair of magnets having core members extending outwardly beyond the ends thereof, a yoke connecting said core members at one end, oppositely facing core extensions secured to said cores at their other ends, a bearing secured to said core extensions, a rod slidably mounted in said bearing and passing through said yoke, an armature secured to said rod and movable between said core extensions, and a spring positioned upon said rod between said armature and yoke.

6. A fuel injector comprising a pair of magnets having core members extending

outwardly beyond the ends thereof, a yoke connecting said core members at one end, 65 oppositely facing core extensions secured to said cores at their other ends, a bearing secured to said core extensions, a rod slidably mounted in said bearing and passing through said yoke, an armature secured to said rod 70 and movable between said core extensions, and a spring positioned upon said rod between said armature and yoke, and adjusting means attached to said bearing member operating upon the end of said rod for 75 regulating the movement of said rod.

7. A fuel injector comprising a pair of magnets having core members extending outwardly beyond the ends thereof, a yoke connecting said core members at one end, 80 oppositely facing core extensions secured to said cores at their other ends, a bearing secured to said core extensions, a rod slidably mounted in said bearing and passing through said yoke, an armature secured to said rod 85 and movable between said core extensions, and a spring positioned upon said rod between said armature and yoke, a supporting bracket attached to said yoke, a pump cylinder attached to said yoke and positioned 90 above said bracket, said rod extending into said pump cylinder to form the piston thereof.

8. A fuel injector comprising a pair of electro-magnets, including core members, a 95 yoke connecting said core members at one end, a pair of core extensions attached to said cores at their other ends, a casing connecting said core extensions having a bearing formed therein, a pump secured to said 100 yoke including a plunger said plunger extending through said yoke and being slidably mounted in said bearing, an armature attached to said plunger adapted to be attracted by said core ends and a spring positioned on said plunger seated between said 105 armature and yoke.

9. A fuel injector comprising a pair of electro-magnets, including core members, a yoke connecting said core members at one 110 end, a pair of core extensions attached to said cores at their other ends, a casing connecting said core extensions having a bearing formed therein, a pump secured to said 115 yoke including a plunger, said plunger extending through said yoke and being slidably mounted in said bearing, an armature attached to said plunger adapted to be attracted by said core ends and a spring positioned on said plunger seated between said 120 armature and yoke, a threaded cap secured to said bearing and a spring positioned within said cap adapted to engage the end of said plunger.

ALBERT R. BEHNKE.
